UNITED STATES PATENT OFFICE.

WARNER B. WRIGHTSMAN, OF KOKOMO, INDIANA.

MAGNETO DRIVING MECHANISM.

1,228,864.

Specification of Letters Patent. Patented June 5, 1917.

Application filed May 18, 1916. Serial No. 98,471.

To all whom it may concern:

Be it known that I, WARNER B. WRIGHTSMAN, a citizen of the United States, residing at Kokomo, in the county of Howard 5 and State of Indiana, have invented certain new and useful Improvements in Magneto Driving Mechanism; and I do declare the following to be a full, clear, and exact description of the invention, such as will enable others skilled in the art to which it 10 pertains to make and use the same.

This invention relates generally to electric ignition generators for internal combustion engines but more particularly to a 15 magneto driving mechanism for such engines.

When it is desired to start an internal combustion engine from rest by turning the engine shaft, a certain speed must usually 20 be attained before the electric ignition generator, or, as it is usually termed, the ignition magneto, will generate a spark to fire the explosive mixture. The turning of the engine shaft is, especially with large engines, 25 very laborious, and it is therefore desirable that the speed of the ignition magneto should be accelerated with relation to that of the engine shaft in order that a spark may be generated while the engine 30 shaft is turning at a speed normally insufficient to produce such a spark.

The primary object of the present invention is to overcome this difficulty by the provision of a device interposed between the 35 shaft of the engine and the shaft of the magneto to cause the latter to rotate at an accelerated speed with respect to that of the engine shaft when the engine is started from rest, said driving mechanism being of 40 such construction that it will be automatically thrown out of operation after the engine has reached a certain speed sufficient to generate the desired spark without the use of an accelerator.

Another object of the invention is to 45 provide an attachment for the usual magneto of an internal combustion engine so that when the engine is cranked the magneto will produce the initial spark to start 50 the engine without the use of a battery.

A still further object of the invention is to provide a device of this character which is of simple, strong, durable and inexpensive construction, efficient and reliable in 55 operation, and well adapted to the purpose for which it is desired.

With these and numerous other objects in view, the invention consists of certain novel features of construction and the combination and arrangement of parts as will be 60 hereinafter fully described and claimed.

In the accompanying drawings, in which similar reference characters designate like parts throughout the several views,

Figure 1 is a side elevation of a device 65 constructed in accordance with this invention, showing its application to the ignition magneto and shaft of an internal combustion engine.

Fig. 2 is a central vertical longitudinal 70 sectional view through the same;

Fig. 3 is a transverse vertical sectional view taken on the line 3—3 of Fig. 2, looking in the direction of the arrows *a*;

Fig. 4 is a similar view taken on the same 75 line, looking in the direction of the arrows *b*;

Fig. 5 is a similar view taken on the line 5—5 of Fig. 2, the latch being here shown in its operative position: 80

Fig. 6 is a similar view showing the latch in its inoperative position;

Fig. 7 is a similar view taken on the line 7—7 of Fig. 2, looking in the direction 85 of the arrows *a*; and

Fig. 8 is a similar view taken on the same line looking in the direction of the arrows *b*.

Referring more particularly to the drawings, the numeral 1 represents a conventional ignition magneto provided with the usual armature shaft 2 adapted to be rotated by a driving mechanism, now to be described, said driving mechanism being in turn connected to a shaft 3 of an internal combustion engine. 90

The above referred to driving mechanism comprises a stationary member or plate 4, which is here shown as having a centrally arranged opening 5 therein, and being circular in configuration, but it is to be understood that it may be of any desired or convenient shape. Extending laterally from the lower edge of the plate 4 is an attaching bracket 6 which is firmly secured by suitable bolts or screws 7 to a stationary part of the magneto 1. The outer side of the plate 4 is provided with an annular flange 8, which is arranged concentric to the aforesaid opening 5, and which is provided on its free edge with a notched-out portion 9. Secured in any suitable manner, but prefer- 100 105 110 115

ably by screws 10, to the outer side of the plate 4 and within the annular flange 8 is a substantially circular ring 11, the latter being likewise arranged concentric to the central opening 5 in the plate 4, whereby to provide in effect a channel or groove 12 between its outer edge and the inner side of the flange 8. The ring 11 is provided on its upper edge with a stop in the form of a notch 13, one of the walls of which is substantially upright, while the other wall is arranged angularly for a purpose to be hereinafter described.

The reference numeral 14 designates a rotating member or disk, which is circular in configuration and provided on one of its sides with an annular flange 15 which abuts the flange 8 arranged on the plate 4, and being provided at its free edge with a notched-out portion 16 to provide a snug engagement with the same. This disk 14 is provided with a centrally arranged opening 17 for a purpose to be hereinafter described, and is provided at opposite sides with hub portions 18 and 19 respectively. The hub portion 18 is larger in diameter than the hub portion 19, and is provided with suitable means for a firm attachment to one end of the shaft 3 of the above referred to internal combustion engine.

As shown in Figs. 2 and 7 of the drawings a volute spring 20 surrounds the smaller hub portion 19 and has one of its ends firmly secured in a slot in the same. The other end of the spring 20 is looped around a pin 21 which extends laterally from one side of a second rotating member or disk 22, the latter being arranged within the housing formed by the plate 4, the disk 14 and the annular flanges 8 and 15, and having hub portions 23 and 24 arranged on its opposite sides. This disk 22 is arranged adjacent the disk 14 with its axis coincident with that of the latter. The hub portion 24 extends into the opening 17 in the disk 14, and is provided on its opposite outer side with flat portions 25 for a purpose to be hereinafter described. It may thus be seen that the rotating disks 14 and 22 are operatively connected to each other by an elastic means, whereby should the disk 14 be rotated while the disk 22 is locked against movement or retarded, and then released, the disk 22 would, under the tension of this elastic means or spring 20, be returned to its normal position at an accelerated speed.

Slidable transversely on one of the sides of the disk 22 is a latch plate 26; the latter having a longitudinally extending slot 27 therein through which extends the aforesaid hub portion 24. This slot is equal in width to the distance between the flat portion 25 of the hub portion 24, whereby said latch plate 26 is prevented from rotating with respect to the disk 22 as will be readily understood.

This latch plate 26 is less in length than the distance between the opposite sides of the disk 22, and is provided at one of its ends with a laterally extending lug 28, the latter projecting through a notch 29 arranged in one edge of the disk 22, and being adapted to be seated in the notch 13 in the ring 11 carried by the stationary plate 4. This lug 28 has its opposite edges arranged angularly so that when it is received in the notch 13 it will prevent the latch plate 26 together with the disk 22 from being rotated in one direction, while it will be readily disengaged from the lug 13 if turned in the opposite direction. This will be readily understood.

One side of the disk 14 is provided with a tripping element in the form of a cam lug 30, which is adapted to engage the end of the latch plate 26 opposite to the end carrying the lug 28, and move said latch plate, and cause said lug 28 to become disengaged from the slot 13. Thus it may be seen that after the disk 22 has been retarded or locked against movement for a short period of time while the spring 20 is being put under tension, it is released, thereby allowing it to rotate to its normal position at an accelerated speed. The cam lug 30 acts also in the capacity of a stop against which a lug 31 carried by the disk 22 bears.

As shown clearly in the drawings, the end of the latch plate 26 which carries the lug 28 is extended on its opposite edges to provide projections 32, the projections adjacent the pin 21 carried by the disk 22 engaging the same and limiting the movement of said latch plate. These projections 32, together with the lug 28 make this end of the latch plate heavier than the other end, said other end being preferably cut angularly to more effectively accomplish this result. By this arrangement it may be seen that when the magneto shaft 2, and consequently the speed of the disk 22 has attained a considerable speed, the heavier end of the latch plate 26 will be retained outwardly or in its inoperative position with respect to the notch 13 by centrifugal force, as will be readily understood.

In operation, when it is desired to start the internal combustion engine equipped with this improved magneto driving mechanism, the shaft 3 of said engine is turned very slowly at first so as to allow the latch plate 26 to drop by gravity when the lug 28 carried by the same is opposite the aforesaid notch 13. Upon further turning of the shaft 3 the disk 22 under the tension of the spring 20 will be locked until the cam lug 30 carried by the rotating disk or member 14 is moved into engagement with the lighter or other end of the latch plate 26. This engagement, as heretofore explained, moves the latch plate upwardly and disengages the lug 28 from the notch 13, thereby allowing the disk

22 to be moved to its normal position at a speed sufficient to generate the necessary spark for firing the explosive mixture in the engine cylinders. When the engine has been 5 thus started, and has reached a speed sufficient to generate the necessary spark without the aid of the accelerator, the latter is thrown automatically out of operation by centrifugal action, in the manner heretofore 10 explained.

From the foregoing description, taken in connection with the accompanying drawings, the construction and operation of the device may be readily understood without a 15 more extended explanation.

As various changes in form, proportion, and in the minor details of construction may be resorted to without departing from the spirit of this invention I do not wish to be 20 limited to the construction herein shown and described other than that set forth in the appended claims.

I claim:

1. A device of the class described comprising a rotating disk adapted to be actuated by an internal combustion engine, a second rotating disk adapted to be attached to the shaft of the magneto of said engine, said disks being arranged adjacent each other 30 and having their axes coinciding, a volute spring arranged between said disks, one end of said spring being attached to one of said disks and the other end to the other disk, a latch mounted upon one of said disks to slide 35 transversely of the same, a stationary stop arranged in the path of said latch and adapted to be engaged by the same to lock its respective disk against movement, and means carried by the other disk for disengaging said latch from said stop when the 40 first disk has been retarded a predetermined amount.

2. A device of the class described comprising a rotating disk adapted to be actuated by an internal combustion engine, a second rotating disk having hub portions extending 45 from the opposite sides thereof and adapted to be attached to the shaft of the magneto of said engine, a volute spring interposed between said members and having its opposite ends connected to the same, a stationary member having a stop thereon, a latch plate 50 slidable on one side of one of said ro-

tating members and having a longitudinal slot therein, to provide for the reception of 55 one of said hub portions, a lug carried by said plate and adapted to engage said stop for locking the last referred to rotating member against movement, and a cam lug carried by the other rotating member and 60 adapted to engage said plate upon the rotation of said other rotating member to disengage the first mentioned lug from said stop.

3. A device of the class described comprising a stationary plate having an annular flange on one side thereof, a rotating disk spaced from said plate and having an annular flange on one of its sides abutting the flange on said plate, to provide a closed housing, a second rotating disk arranged within said housing, a volute spring interposed between said disk and having its opposite ends connected to the same, a stop arranged on said plate, a latch slideable on the last named 75 disk and adapted to engage said stop for locking said last named disk against movement, and a cam carried by the other disk and adapted to engage said latch when the former disk has been retarded a pre-deter- 80 mined amount.

4. A device of the class described comprising a pair of rotating members having elastic means operatively connecting the same together, a latch plate slidably mounted on 85 one of said members and being heavier at one end than at the other, whereby it is caused to move into an inoperative position by centrifugal force when rotated rapidly, a lug carried at the heavier end of said plate, 90 a stationary member having a notch in its outer side for receiving said lug when said plate is rotated slowly, whereby to retard the movement of the last mentioned rotating member, and a cam carried by the other ro- 95 tating member and adapted to engage the other end of said plate when the former rotating member has been retarded a pre-determined amount.

In testimony whereof I have hereunto set 100 my hand in presence of two subscribing witnesses.
